UNITED STATES PATENT OFFICE.

HENRY M. REICHENBACH, OF YONKERS, NEW YORK.

OIL-BURNER.

No. 829,890.

Specification of Letters Patent.

Patented Aug. 28, 1906.

Application filed March 2, 1903. Serial No. 145,785.

To all whom it may concern:

Be it known that I, HENRY M. REICHENBACH, a citizen of the United States, residing at Yonkers, in the county of Westchester 5 and State of New York, have invented certain new and useful Improvements in Oil-Burners; and I do hereby declare the following to be a full, clear, and exact description of the invention, such as will enable others skilled in the art to which it appertains to make and use the same.

My invention relates to improvements in oil-burners; and the object of my invention is to provide an improved downdraft-burner 15 simple and inexpensive to make, effective in working, and adapted to burn any kind of crude-petroleum oil.

My invention is more especially adapted for use in boiler-furnaces; but it is not restricted to such a use.

With these objects in view my invention consists of the construction and combinations of parts, as hereinafter described and claimed.

25 In the accompanying drawings, Figure 1 is a vertical cross-section of one form of my improved burner. Fig. 2 is a plan view of one of the distributing-disks. Fig. 3 is a cross-section of the same. Fig. 4 is a plan 30 view of the burner. Fig. 5 is a plan view representing three burners arranged in a battery. Fig. 6 shows my invention applied to a particular form of water-tube boiler. Fig. 7 is a cross-section of another modified 35 form, showing also means for feeding the oil to the burner.

The main features of my invention are that a downdraft is used, the oil being allowed to drip through the burner from the top to the 40 bottom, the lighter and more inflammable portions thereof burning in the upper part and heating by direct contact the heavier constituents of the oil as they descend. The oil is fed by gravity, and any safety device may 45 be interposed between the supply and the burner—such as a water seal, for example.

Referring to Figs. 1 to 4, *a* represents an oil-supply pipe divided into branch pipes *b* and *c*. The pipe *b* in turn is divided into pipes *d* and 50 *e*, the lower end of the pipe *e* connecting with the pipe *c* by a pipe *f*. Resting on the coupling *g*, which connects the pipes *e* and *f*, is a distributing-disk *h*. Resting on this disk is a sleeve *i*, and resting on this sleeve is a second 55 disk *h*, which supports a second sleeve *i*. This structure is continued up as far as is desired.

Just above the top disk the pipe *e* is provided with small perforations *j*, which permit the oil to flow down said pipe onto the top disk. Each of these disks *h* is provided with an annular 60 trough *k* near its edge and a series of perforations *l*—four in number in Fig. 2, although any desired number may be used. The pipe *d* is located directly over the trough *k* in the top disk and serves to return any vapor that 65 may be generated in the feed-pipes into the interior of the burner. The oil may be fed in either through the pipe *b* or the pipe *c*, or both at once. These distributing-disks are centrally located in a casing *m*, made of metal 70 or other heat-resisting material. This casing *m* is provided with a fixed top *n*, having a number of apertures therein, over which is placed a second movable top *o*, having apertures *p* therein, which construction acts as a 75 damper.

Connected to the casing *m* near its top is an air-pipe *q*, provided with a damper *r*, having a handle *s*, which pipe communicates with the stack. This pipe is used in starting up the 80 burner. The damper *r* is opened, and the oil ignited from the door *z*. The flame then passes upwardly through the burner, and the products of combustion pass through the pipe *q* into the stack. After the burner is 85 heated up the damper *r* is closed and the dampers in the casings *m* and *t* are opened. This immediately produces a downdraft, the products of combustion passing out through the open end of the casing *m*. The burner is 90 therefore started as an updraft-burner, and after it is heated up it is transformed into a downdraft-burner in the manner described. Outside the casing *m*, below the pipe *q*, is a 95 larger casing *t*, provided with a fixed top *u*, having apertures *v* therein. Above the fixed top *u* is a movable top *w*, having apertures *x*, which construction serves as a damper.

A pipe *y* passes through the casings *m* and *t* and is closed by a door *z*, which affords a 100 peep-hole into the interior of the burner and through which the oil is lighted when the burner is started up. Passing through the casing *m* and located centrally of the outlet end thereof is a pipe *2*, provided with a damper *3*, having a handle *4*. This pipe may be connected to a blower to force air through the burner, or it may be simply connected to the outer air, said air being drawn into the pipe *2* by the outrush of the gases of combustion. 105 This pipe *2* rests on the ridge *5* in the interior of the casing *m*, and a spider-frame (not

shown) may be used to keep said air-pipe 2 in the center of the casing *m*.

The operation is as follows: Oil is allowed to flow through the pipes *b* or *c* out through the apertures *j* and drips down over the disk *i*. A lighted match or similar device is inserted through the door *z*, lighting the oil as it flows down, and the damper *r* is opened, whereupon the oil commences to burn quickly. As soon as the whole burner becomes heated up the oil is vaporized and a strong draft is induced through the casing *m*, the damper *r* is closed, and the air supplied through the tops of the casing *o* and *w*. As the vaporized oil, partially consumed, flows down out through the casing *m* it is joined by a current of heated air drawn in between the casings *m* and *t* and through the pipe 2, supplying air to the center of the flame, making an intensely hot flame and consuming every particle of the oil.

The disks *h* and the sleeves *i* are shown made of cast-iron; but in case of a forced draft they may be made of other more refractory material. The same is true of the casing *m*.

In Fig. 6 I have shown my burner applied to a form of boiler having spirally-arranged water-tubes. 57 represents the burner, and 58 the tubes. The flame is driven downwardly from the burner upon the tubes, then upwardly, coming in contact with other turns of the tube.

In Fig. 7 another modification is shown. 35 This modification is similar to that shown in Fig. 1 in the arrangement of casings; but the central support 59 is a tube branched at the top. This tube is for the double purpose of admitting air into the center of the flame and 40 at the same time keeping the tube cool and preventing it from warping under the intense heat generated. At its lower end the tube is supplied with a supporting-nut 60, on which are mounted the distributing-disks 62, which 45 fit around the tube 59. In Fig. 7 these disks are shown as solid; but any form of disk may be used—as, for instance, the form shown in Figs. 1 to 3.

63 represents a closed oil-tank, and 64 a pipe entering the top of said tank, which pipe may be removed for filling the tank 63 with oil. A delivery-pipe 65, provided with a stop-cock 66, leads from the bottom of the tank 63 into an open-top vessel 67, from 55 which a pipe 68, provided with a stop-cock 69, leads into the water seal 70, from the top of which the pipe 71 delivers the oil to the disks 62 in the interior of the burner. The water seal 70 in use is about half filled with 60 water. By opening the cock 66 oil will flow out from the tank 63 into the vessel 67 until it reaches and covers up the lower end of the open pipe 64, when the flow of oil will cease, because no air can enter through the pipe 64 65 into the tank 63. By opening the stop-cock

69 the oil will then flow through the pipe 68 into the water seal 70, bubbling up through the water, and thence through the pipe 71 onto the disks 62. By the means above described the flow of oil can be accurately regulated.

Having thus described my invention, what I claim as new, and desire to secure by Letters Patent of the United States, is—

1. In an oil-burner, the combination of means for producing a downdraft, an oil-delivery pipe, and a series of perforated trough-shaped devices for distributing said oil mounted on said pipe, said pipe being perforated so as to deliver oil to one of said devices, substantially as described.

2. In an oil-burner, the combination of means for producing a downdraft, an oil-pipe, a series of superposed distributing devices for said oil parallel to each other and located on said pipe, each device having a trough-shaped portion and provided with perforations, and means for supporting said devices one above the other on said oil-pipe, substantially as described.

3. In an oil-burner, the combination of a casing, means for producing a downdraft in said casing, a perforated oil-pipe in said casing, distributing devices for the oil mounted on said oil-pipe, sleeves separating said devices from each other, each of said devices having a trough-shaped portion and being provided with perforations, and said oil-delivery pipe being provided with a portion bent upon itself and delivering into said casing, substantially as described.

4. In an oil-burner, the combination of a casing, means for producing a downdraft in said casing, an oil-delivery pipe, provided with perforations, passing through one end of said casing, distributing devices mounted on said oil-pipe, said distributing devices being perforated and each having a trough-shaped portion, and means for admitting air to the central part of the delivery end of said casing, substantially as described.

5. In an oil-burner, the combination of a casing, means for producing a downdraft in said casing, said casing being provided with air-apertures of variable size at one end, an oil-pipe passing into said casing and provided with perforations, and a series of distributing devices located on said oil-pipe, each of said distributing devices being perforated and being provided with a trough-shaped portion, substantially as described.

6. In an oil-burner, the combination of a casing, one end of which is provided with air-apertures of variable size, means for producing a downdraft in said casing, a perforated oil-pipe passing into said casing, a series of distributing devices mounted on said oil-pipe, each of said devices being perforated and provided with a trough-shaped portion, and a second casing surrounding and parallel

to said first-named casing, one end of said second casing being provided with air-apertures of variable size, substantially as described.

5 7. In an oil-burner, the combination of a casing, a pipe connected thereto for supplying air under pressure, one end of said casing being provided with air-inlets of variable size, an oil-pipe delivering into said casing, said 10 oil-pipe being provided with perforations, a series of distributing devices mounted on said oil-pipe, each of said devices being perforated and provided with a trough-shaped portion, a series of sleeves supporting and separating 15 said devices, said oil-pipe being provided with a bent-over portion entering said casing, a second casing encircling the first-named casing and parallel thereto, one end of said second casing being provided with air-inlets of

variable size, and a pipe centrally located in 20 the delivery end of said first-named casing to deliver air to the center of the flame, substantially as described.

8. The combination of boiler-tubes and a battery of burners, each burner comprising a 25 pipe acting as a central support, a series of separated superposed oil-distributing devices mounted on said pipe, said pipe delivering oil to said devices, and means for delivering oil to each of said burners, substantially as described.

In testimony whereof I affix my signature in presence of two witnesses.

HENRY M. REICHENBACH.
